UNITED STATES PATENT OFFICE.

CHARLES H. KOLLING AND REINHOLD PRIETZ, OF JERSEY CITY, NEW JERSEY, AS-SIGNORS OF THREE-EIGHTHS TO OSCAR O. LAUCKNER, OF HOBOKEN, NEW JERSEY, AND THREE-EIGHTHS TO OSCAR A. WEISSENBORN, OF JERSEY CITY, NEW JERSEY.

MECHANICAL THEFT ALARM FOR AUTOMOBILES.

Application filed February 11, 1924. Serial No. 691,917.

To all whom it may concern:

Be it known that we, CHARLES H. KOLLING and REINHOLD PRIETZ, both citizens of the United States, both residing at Jersey City, county of Hudson, and State of New Jersey, have invented certain new and useful Mechanical Theft Alarms for Automobiles, of which the following is a specification.

10 This invention relates to a mechanical theft alarm for motor vehicles and is directed to the same general type of protection as the subject matter of our companion application, Serial No. 673,869, filed on November 10th, 1923, except that while the said copending case is directed to a theft alarm in which the alarm is actually given through the employment of electrical means, the present construction operates in a purely 20 mechanical manner.

The present invention depends for its operation upon the utilization of a pendulum which in the event of theft is disturbed from the position in which it is normally maintained by gravity and through this disturbing influence occasioned by unauthorized operation of the car, brings about the actuation of alarm means. In its broad sense, the present invention is similar to our prior invention, although in the present case the alarm means set into operation through actuation of the pendulum is wholly different from that heretofore suggested by us. Thus while certain broad claims to the pendulum arrangement may be at the same time applicable to both constructions, claims to the pendulum control mechanism will widely differ.

The object of the present invention is to 40 provide an alarm mechanism which is entirely mechanical and in the operation of which the utilization of electrical energy is not required. The underlying principle of the invention involves the employment of an alarm adapted to be actuated by a motor which in practice may be a spring motor and the operations of which motor are controlled by a pendulum which under normal conditions maintains the motor in restraint but which under the disturbing influence of attempted theft will release the motor and permit of its operation to cause

an alarm to be given. The motor may be energized manually or if desired a spring motor if employed may be automatically wound by suitable electrical means, but it will be noted that this electrical means simply serves to keep the motor in an energized condition and ready for operation, mechanical means being utilized to actually give the alarm.

In its preferred practical form, the pendulum which controls the giving of the signal embodies two links, one of which is suspended on the other and both of which are suspended on a common pivot. The lower link is weighted and under ordinary driving conditions, the pendulum will swing on the common pivot with both links thereof swinging in alinement. When it is desired to condition the apparatus to give an alarm which is the case when the car with which the device is associated is to be left standing alone, the upper link of the pendulum combination is locked against pivotal movement on the common pivot, so that if the car is moved the disturbing influence of such movement will cause the swinging of the lower link of the pendulum independently of the upper link. A slide is associated with the upper link and has a cam-like connection with the lower link so that when the lower link swings independently of the upper link the slide will be operated and through such operation will trip a detent which holds the motor in restraint. As a result, the motor will be caused to operate and will effect the giving of an alarm.

The structure is extremely simple though absolutely positive in its operation.

Features of the invention, other than those specified, will be apparent from the hereinafter detailed description and claims, when read in conjunction with the accompanying drawings.

The accompanying drawings illustrate the preferred practical embodiment of the invention.

Figure 1 is a side elevation of alarm mechanism embodying the present invention.

Figure 2 is an end view of the apparatus shown in Figure 1.

Figures 3 and 4 are diagrammatic illus-

trations showing the operation of the apparatus illustrated in the preceding figures.

Figure 5 is a diagrammatic showing of automatic electrical rewinding means for re-energizing the spring motors shown in Figures 1 and 2; and,

Figure 6 shows a part of the structure of Figure 5 in a different operative position than that shown in the preceding figure.

Referring to the drawings and more particularly to Figures 1 and 2, 1 designates a frame of any suitable construction shown as embodying two plates 2 and 3 rigidly spaced apart and supported on suitable brackets 4. Between the plates forming this frame is supported a spring motor 5 mounted on a shaft 6, the opposite ends of which are journaled in the plates 2 and 3 of the frame. The spring motor may be of any approved construction and is provided with a winding gear 7 and driven gear 8. The energizing of the spring is accomplished through the winding gear 7 and in the form of the invention shown in Figures 1 and 2, rotation may be imparted to this gear by a pinion 9 fixed on a winding spindle 10 and the upper end of which has associated therewith a key 11 by which it may be turned to wind up the spring.

The gear 8 meshes with a pinion 12 mounted on a counter shaft and with which pinion the gear 13 is rigid. The gear 13, in turn, meshes with a pinion mounted on or formed integral with an escapement shaft 14, one end of which projects through and beyond the plate 2 and has affixed to the outer end thereof a ratchet wheel 15, best shown in Figure 2.

As the spring unwinds, it drives gear 8 and through the connections described effects rotation of the ratchet wheel 15, which, in turn, acts upon an escapement yoke 16 pivoted at 17 (see Figure 2) and in so doing imparts a vibratory movement to this yoke.

Affixed to the yoke is the stem 18 of a clapper 19 adapted, when vibrated, to coact with and operate upon the bell 20 for the purpose of giving an audible alarm. The unwinding operation of the spring is timed by means of a ball governor 21 associated with the shaft 22 and journaled at its opposite ends in the plates 2 and 3 as shown in Figure 1. This shaft 22 has a pinion 23 fixed thereon and this pinion meshes with a gear 24 fixed on the escapement shaft 14, as shown in Figure 2, so that through the gearing described, the speed of the unwinding of the spring motor may be controlled.

From the description as thus far advanced, it will be apparent that we provide a bell and mechanical power means for ringing the bell when said power means is

in operation. The structure shown for this purpose is thoroughly practical and efficient and economical to manufacture though this structure may vary somewhat from that described without departing from this invention. The fundamental requisite is that the structure will embody an alarm which may be sounded but the means which sounds the alarm must be normally held in restraint so that the alarm will not be given inadvertently or when not desired.

This end in the construction shown is accomplished by employing a brake in conjunction with the governor and which brake is normally set to hold the motor in restraint, but which will permit the operation of the motor when the brake is withdrawn. Thus, in Figure 1, the governor is shown as provided with a brake disc 25 and with this disc 25 cooperates a brake arm 26 having a brake shoe 27 associated therewith and adapted to engage the disc 25. The brake arm 26 is secured by means of rivets 28 or otherwise on a detent lever 29 pivoted on a bracket 30 formed on and secured to the plate 3 (see Figure 1). The screw 31 constitutes the pivot of this detent lever. A spring 32 normally impels the lever 29 in a direction to disengage the brake shoe from the disc, but the shoe is normally in engagement with the disc and against the tension of the spring 32 by means of a stop arm 33. This stop arm is pivoted at 34 on the frame and is offset or otherwise provided with a shoulder 35 which normally lies in the path of the upper end of the detent lever and restrains said lever against movement by the spring 32, holding it in a position to brake the governor. The weight of the stop arm 33 normally precludes its disengagement from the detent lever and holds the parts in restraint until such time as the free end of the stop arm is lifted sufficiently to release the detent lever and permit the spring motor to function.

The means for accomplishing the lifting of the stop arm at certain predetermined times and at no others forms an important part of this invention which will now be described.

Extending from the plates 2 is a bracket 35 carrying a pivot 36 on which is supported a pendulum consisting of two links 37 and 38. The upper end of the link 37 is secured to the bracket 35 by the pivot 36, while the upper end of the link 38 is pivoted by means of a screw 39 to the lower end of the link 37. The lower end of the link 38 is provided with a suitable weight 40. Under ordinary conditions, the weight 40 will cause the links 37 and 38 to gravitate into vertical alignment and if a swinging motion be imparted to the

pendulum both links will swing simultaneously while maintaining their alinement. Moreover, while thus swinging in unison, the pendulum will carry with it a slide 41 mounted for vertical sliding movement between guides 42 on the upper link 37. The upper end of the slide 41 is rounded over and is adapted for cooperation with a curved portion 43 in the under side of 10 the stop arm 33, this curved portion 43 being struck on substantially the center of the pivot 36, so that as the pendulum swings, no movement will be imparted to the stop arm.

15 The lower end of the slide 41 is cut out to receive a portion of the upper end of the link 38, but is provided at its extreme lower end with shoulders 44 adapted for cooperation with shoulders 45 formed adjacent the 20 upper end of the link 38 in the event that the link 38 is swung out of alinement with the link 37. Manifestly the pivotal movement of the link 38 on the screw 39 while the link 37 is held rigidly against such rotation as would keep the links in alinement, will cause the shoulders 44 and 45 to cooperate to shift the slide 41 upwardly and thereby cause pressure against the under side of the arm 33. The same result will be 25 accomplished if instead of providing the shoulders 44 and 45, the lower end of the slide had a cam or eccentric connection with the upper end of the link. In any event, the brake will be released and the alarm given, 30 if the upper link 37 is held rigid and the lower link 38 oscillated since there will result from this operation an elevation of the slide 41 which will lift the stop arm 33 and disengage the detent lever 29, so that the 35 spring 32 will thereupon release the brake and allow the motor to operate and ring the bell.

Under ordinary conditions of running a car, it is not desirable to give a theft alarm, 40 so that normally the two links will be left free to oscillate in unison while maintaining their alinement, but means is provided whereby the link 37 may be locked against pivotal movement on its pivot 36 when the 45 car is to be left unaccompanied, so that any attempt to thereafter move the car will result in a disturbing of the equilibrium of the lower link 38 and occasion a setting off of the alarm.

50 In order to thus lock the upper link, when occasion demands, said upper link is formed in its lower portion with a segmental retaining portion 46 in the form of a flange extending rearwardly from the lower end of the link as shown in Figure 2 and this segmental flange is struck on a center of the pivot 36. With the flange 46 is adapted to cooperate a retainer 47 carried by a bracket 48, which is in turn mounted on an arm 49.

The arm 49 is pivoted at its lower end to the bracket 30 by a screw 50 and its upper end is impelled by means of a spring 51 in such direction as to force the retainer 47 into engagement with the segmental flange 46. Associated with the apparatus however 55 is a lock 52 having a bolt 53, the outer end of which is turned up and is adapted thus to engage the inturned upper end 54 of the arm 49, shown best in Figure 2. The position of the bolt 53 is adapted to be controlled by a key 55 and under normal conditions when it is desired to run the car without giving an alarm, the key is actuated to retract the bolt 53 and cause the hook end of the bolt to swing the arm 49 against 60 the tension of the spring 51 and into a position wherein the retainer 47 will be withdrawn from contact with the flange 46.

Associated with the arm 49 is a stop 49' which, when the bolt is retracted, will press 65 against the brake lever 29 above the pivot 31 and thus hold the brake 27 in engagement with the brake disc 25. Under these conditions, it will be apparent that any movements of the car which would cause 70 oscillation of the pendulum will swing the pendulum as a unit upon the pivot 46 and during which swinging movement, the links 37 and 38 will maintain their substantial alinement and no longitudinal movement 75 will be imparted to the slide 41. Moreover the brake will be locked in set condition by the stop 49' as well as the shoulder 35.

When it is desired to leave the car under the protection of the alarm apparatus, the 80 key 55 is operated to advance the bolt 53 into the position shown in Figure 1 and the key is thereupon withdrawn and kept in possession of the driver. As the bolt moves forward into the position of Figure 1, the 85 spring 51 will cause the retainer to engage the flange 46 and thus lock the upper link 37 against pivotal movement. At the same time, the stop 49' will be moved free from the brake lever 29, leaving said lever locked 90 in place to set the brake, only by the shoulder 35. If operation of the car is now attempted, the link 38 will be disturbed and will oscillate with the result that the slide 95 41 will elevate the arm 33 and release the brake lever 29 whereupon an alarm will be given as hereinbefore described.

In practice the keyhole of the lock 52 is so configurated that the key can be withdrawn only when the bolt is retracted. By 100 this arrangement the withdrawal of the key when the driver leaves the car will insure that the apparatus is left in a condition to afford protection to the car.

The advantage of employing a flange 46 105 of arcuate configuration struck on the center of the pivot 36 is inherent in the fact that a car may be stopped on a grade and the

retainer brought into locking position irrespective of such grade. This will be apparent from Figures 3 and 4 of the drawings. In the former figure, we have shown the parts as locked in position with the car standing on a level and in dotted line position, the parts are illustrated at the instant when movement of the car releases the alarm mechanism for operation.

10 In Figure 4, however, we have shown the position which the parts will assume if the car is stopped on a grade. In this figure, the retainer is shown as locking the upper link against pivotal movement by its engagement with a different portion of the flange than that portion which it is engaging in Figure 3. However, irrespective of the part of the arcuate flange engaged by the retainer, the upper link will be locked 15 against oscillation and subsequent attempt 20 to operate the car will cause the sounding of the alarm.

The whole apparatus is in practice housed within a suitable casing preferably of sheet 25 metal provided with a hole through which the key or keys may be passed to actuate the lock or to wind the spring. The casing however is so constructed that it will be strong and will resist breakage by unauthorized persons and at the same time will preclude tampering with the mechanism enclosed therein. The parts of the apparatus are compactly assembled within this casing which may be relatively small thereby 30 adapting it to be positioned in any suitable and convenient location such for example as directly back of the instrument board where the keys can be readily manipulated.

In forming the metallic casing, the casing 35 is preferably provided in at least one side thereof with perforations through which the ringing of the bell may be heard and in order to preclude tampering with the apparatus by sticking wires or implements 40 through the perforations thus provided, these perforations are preferably covered interiorly of the casing with a partition constituting the baffle plate. This partition may also be perforated by holes positioned 45 out of alignment with the perforations in the wall of the casing and the partition is moreover preferably spaced a short distance 50 from the wall of the casing and interiorly thereof so as to allow of the free exit of 55 the sounds produced by the ringing bell.

In the construction thus far described, the operations are wholly mechanical, the spring motor being energized by a manually operable key. In practice, however, we may 60 arrange to have the spring motor energized or wound automatically. Such an arrangement is shown in Figures 5 and 6. In the former figure 5 designates the spring motor with its winding and driven gears 7 and 8.

The winding gear in this showing is adapted to be driven from an electric motor 60. The driving connections between these parts constitute a worm 61 fixed on the armature shaft 62 of the motor and meshing with the worm wheel 63 fixed on a counter shaft 64 which carries a pinion 65 meshing with the winding gear 7. When the electric motor 60 is energized, the spring motor will be wound. In order to automatically control the winding of the spring motor, and effect rewinding thereof when the spring has run down, we employ an automatic control which will now be described. The operating wires for the motor are designated 66 and 67 which lead respectively to a switch arm 68 and a fixed contact 69. In the lead 66 is included a suitable source of electrical energy 71. A switch arm 68 is pivoted at 70 and is adapted to be oscillated between the arms 72 and 73 by means of a revolving drum 74 pivoted for oscillation on a pin 75. Fixed to the drum is a bracket 76, the end of which is bifurcated to straddle a follower 77 having threaded connection with a spindle 78 and on the spindle 78 is fixed a pinion 79 which meshes with the winding gear 7. The follower 77 is in the form of a gear which meshes with a fluted shaft or elongated arbor 80 having a fixed pinion 81 meshing with the driven gear 8 of the spring motor. The arbor 80 and spindle 78 are fixed against longitudinal movement.

Extending from the periphery of the drum 74 and rigidly secured thereto is a 100 leaf spring 82, the outer end of which passes through a perforation in an upstanding lug 83 on the switch arm. The opposite end of the switch arm is provided with a further upstanding lug 84 adapted to cooperate with 105 the drum and under certain conditions to pass through openings 85 and 86 in the skirt of the drum as will presently be described.

In operation the parts are so adjusted that as the motor unwinds with consequent 110 rotation of the gear 8, the arbor 80 will be rotated and will serve to rotate the pinion 77. Inasmuch as the gear 7 remains at rest during the unwinding of the spring, the spindle 78 will be stationary during this period and as a result the pinion 77 will be caused through rotation of the arbor 80 to travel longitudinally of the spindle 78 in a direction to the right in Figure 5. This travel of the follower will cause the drum 74 to be rotated while the switch arm 68 remains stationary being locked against rotation by engagement of the lug 84 with the inner periphery of the drum as shown in Figure 6. However, as the drum is rotated, the spring 82 is placed under such tension as to immediately impel the switch arm 68 in a direction to engage the contact 69 as

soon as the lock 84 is brought opposite the opening 86 in the drum. The operation described continues until the lock 84 and opening 86 are alined whereupon the tension of the spring 82 will immediately throw the switch arm into engagement with the contact 69 and complete the circuit through the motor 60 and the motor will immediately commence to operate. As the motor 10 winds up the spring, the gear 7 is rotated but the gear 8 remains stationary with the result that the arbor 80 will be stationary while the spindle 78 will be rotated by the pinion 79 and the follower 77 will be moved 15 to the left in Figure 5 thereby placing the spring 82 under tension in the opposite direction from which it is shown in Figure 5 and as it is shown in Figure 6. This operation continues until the spring is wound 20 up by which time the follower will have moved the drum 74 into position to bring the aperture 85 into alinement with the lug 84 whereupon the spring will throw the lug 84 again to the interior of the drum from 25 the position shown in Figure 6 and the operations described will be repeated. It is to be understood that the drum is either circumferentially slotted to permit the switch arm 68 to project thereinto or said switch 30 arm may work at the end of the drum and the openings 85 and 86 may be cut inwardly from the extreme end of the drum. Either construction will give satisfactory results. The use of the drum thus constructed is 35 for the purpose of switching the current to the electric motor off and on and permitting of sufficient interval of operation of the motor to effect proper rewinding of the spring motor.

40 The gearing described is so constituted that proper operation of the parts will result and in practice, this is readily achieved through using gearing of proper ratio. The stops 72 and 73 are merely to preclude 45 overtravel of the switch arm in either direction.

In practice, the alarm mechanism of this invention may be mounted in any convenient position on the car to be protected 50 thereby and will be found to give thorough and efficient protection against theft. The drawings show the invention in its preferred form, but inasmuch as slight structural changes may be made without departing 55 from the spirit of this invention, the invention is to be understood as fully commensurate with the appended claims.

Having thus fully described the invention, what we claim as new and desire to secure by Letters Patent is:

1. A theft precluding device embodying a bell, a spring motor, escapement mechanism associated with the spring motor and comprising a clapper for sounding the bell

when the motor is operated, a governor associated with the motor to time its speed of operation, means for normally braking the motor, a gravity member to which the braking means is normally irresponsive, and means for rendering the braking mechanism responsive to the operations of the gravity member whereby the gravity member may release the motor for operation. 65

2. A theft precluding device embodying an alarm, means normally held in restraint 75 for actuating the alarm, a plurality of gravity members mounted to oscillate simultaneously about the same pivot and independently on different pivots, means for locking one of said gravity members against oscillation, and means operable through the oscillation of the remaining gravity member while the first is locked to release the alarm sounding means and cause the giving 80 of an alarm.

3. A theft precluding device embodying an audible alarm, a motor normally held in restraint for sounding the audible alarm, brake mechanism for normally holding the motor in restraint, a pair of links pivoted 90 to one another and adapted to normally oscillate under the influence of gravity about a common pivot, means for retaining one of the links against oscillation but permitting the oscillation of the other link, and means operable by the independent oscillation of the last mentioned link for releasing the brake and causing the alarm to be sounded. 95

4. A theft precluding device embodying 100 alarm means, alarm braking means, a retainer for normally maintaining said braking means in set condition, a toggle, the terminal end of one link of which is pivoted adjacent said retainer, while the terminal end of the other link is weighted to normally maintain said links in alinement, means for arresting movement of the toggle at its elbow to secure the upper link against movement while permitting pivotal movement of the lower link, and a retainer tripping device carried by the upper link and having a cam surface cooperating with a cam surface on the lower link and operable 105 thereby when the lower link is moved relative to the upper link for the purpose of actuating the tripping device to release the retainer, whereby the alarm means is permitted to operate. 110

5. A theft precluding device embodying 120 alarm means, alarm braking means, a retainer for normally maintaining said braking means in set condition, a toggle, the terminal end of one link of which is pivoted adjacent said retainer, while the terminal end of the other link is weighted to normally maintain said links in alinement, key controlled means for arresting movement of the toggle at its elbow to secure the upper link 125

against movement while permitting pivotal movement of the lower link, and a retainer operating slide carried by the upper link and having a cam surface cooperating with 5 a cam surface on the lower link and operable thereby when the lower link is moved relative to the upper link for the purpose

of actuating the slide to release the retainer, whereby the alarm means is permitted to operate.

In testimony whereof we have signed the foregoing specification.

CHARLES H. KOLLING.
REINHOLD PRIETZ.
